UNITED STATES PATENT OFFICE.

CHARLES A. BENNETT, OF TAUNTON, MASSACHUSETTS.

DESIGN FOR A HANDLE FOR SPOONS, FORKS, OR SIMILAR ARTICLES.

SPECIFICATION forming part of Design No. 36,412, dated July 7, 1903.

Application filed March 7, 1903. Serial No. 146,765. Term of patent 14 years.

To all whom it may concern:

Be it known that I, CHARLES A. BENNETT, of Taunton, in the county of Bristol and State of Massachusetts, have invented a new, original, and ornamental Design for a Handle for Spoons, Forks, or Similar Articles, of which the following, taken in connection with the accompanying drawings, is a specification.

Figure 1 is a front plan view of a fork or spoon, showing my design; and Fig. 2 is a plan view of the opposite or rear side of the fork or spoon.

Having described my invention, what I

claim as new, and desire to secure by Letters Patent, is—

The ornamental design for the handle of a spoon, fork or similar article, as herein shown.

In testimony whereof I have signed my name to this specification, in presence of two subscribing witnesses, on this 10th day of February, A. D. 1903.

CHARLES A. BENNETT.
